UNITED STATES PATENT OFFICE.

FRED S. FULLER, OF EATON, COLORADO.

SACK-HOLDER ATTACHMENT FOR POTATO-SORTERS.

1,080,685.

Specification of Letters Patent.

Patented Dec. 9, 1913.

Application filed November 22, 1911, Serial No. 661,741. Renewed April 28, 1913. Serial No. 764,263.

To all whom it may concern:

Be it known that I, FRED S. FULLER, a citizen of the United States, residing at Eaton, in the county of Weld and State of Colorado, have invented certain new and useful Improvements in Sack-Holder Attachments for Potato-Sorters, of which the following is a specification.

This invention relates to new and useful 10 improvements in sack holder attachments for potato sorters and the like.

An object of this invention is the provision of a device of the above named class which will support a sack or sacks in a convenient position relative to a potato sorter and in such manner that they can be readily removed without danger of injury to the operator.

Another object is the production of an attachment for the purpose described which will hold the mouths of various sized sacks in their extended positions.

A further object of this invention is to improve and simplify devices of this character, rendering them comparatively simple and inexpensive to manufacture, reliable and efficient in use and readily operated.

In effecting these several desiderata, this invention resides in the novel features of 30 construction, formations, combinations and arrangements of parts to be hereinafter more fully described, claimed and illustrated in the accompanying drawings in which:

Figure 1 is a side elevation of a portion 35 of a conventional form of a potato sorter having my invention applied thereto; Fig. 2 is a top plan view thereof; Fig. 3 is an end view thereof, and Fig. 4 is a horizontal sectional view taken on the line 4—4 of 40 Fig. 3.

Referring to the drawings by similar characters of reference, throughout the several views, the numeral 10 designates a conventional form of a potato sorter, comprising 45 a base 11, from which extend the vertical bars 12 which support the usual sorter frame 13, the adjacent vertical bars 12 are united by a transversely disposed, horizontal supporting bar 16.

50 A pair of U shaped brackets 17, is attached in any suitable manner to the inner or rear side of the bar 16 and each is formed adjacent the terminals of its bight portion with apertures through which and through 55 openings provided in the said bar 16, extend

forwardly diverging sliding rods 18 which are forced normally outwardly by coil springs which surround the same between the adjacent faces of the bar 16 and brackets 17. Each rod 18 is provided at its outer end 60 with a forwardly curved hook 19 adapted to engage one side of the mouth of a sack 20.

A lever 21 is pivoted as indicated at 22 at its inner end to the front side of the bar 16 and extends beyond the end thereof a 65 slight distance at which point it is bent upwardly as at 23 terminating in an operating head 24. Each of said levers 21 is offset between its ends and pivoted to the intermediate portion of a catch bar 25 the ends 70 thereof being offset and sharpened to produce prongs 27 which are slidably located in eyes 26 located at either end of the said bar 16. These prongs 26 serve to engage the opposite side of the sack mouth to the one engaged by the hooks 19.

Bars 28 formed preferably of angle material are secured to the ends of the bar 16 and have springs 29 connected thereto, which springs are also connected to the 80 levers 21 serving to normally force the same upwardly retaining the prongs 26 in their uppermost positions. Wear plates 30 are secured to the front faces of the bar 16 in the rear of the levers 21, and are offset at 85 their lower ends producing stops 31 which limit the downward movement of the said levers to an extent that will prevent the disengagement of the prongs 26 from the eyes 27.

90 A sack is applied to the device as follows: One edge of the mouth of the sack 20 is engaged by the prongs 26 after which the rods 18 are forced inwardly against the tension of the coil springs until the hooks 19 engage the opposite side of the sack mouth. This 95 obviously retains the mouth in an open position and permits the opposite end of the sack to rest upon the base 11.

When it is desired to release the sack, all 100 that is required is to force the proper lever 21 downwardly causing the prongs 26 to drop through the eyes 27, obviously freeing the same from the sack.

105 From the foregoing disclosures taken in connection with the accompanying drawings it will be manifest that a sack holder attachment for potato sorters is provided for which will fulfil all of the necessary requirements of such a device, it of course be- 110

ing understood that various minor changes in the details of construction can be resorted to within the scope of the appended claims, without departing from, or sacrificing any of the advantages of the invention.

Having thus fully described this invention, what I claim as new and desire to protect by Letters Patent is:

1. The combination with a bar, of rods 10 movable therethrough, hooks upon said rods, a lever pivoted to the said bar, a sliding bar operated by the lever, prongs formed upon the ends of said bar, and guides engaging the prongs.
- 15 2. The combination with a bar, of a bracket secured thereto, rods movable through the bar and bracket, a lever pivoted to the bar, a sliding bar operated by the lever, prongs formed upon the sliding bar, 20 eyes secured to said bar surrounding the prongs hooks upon the rods, a wear plate

for the lever, and a stop provided upon the wear plate for the lever.

3. The combination with a frame bar, of a bracket secured thereto, rods passing 25 through the bracket and bar, hooks upon the rods, springs engaging the rods, a lever pivoted to the bar, a sliding bar carried by the lever, prongs formed upon the sliding bar, eyes carried by the frame bar and engaging 30 the prongs, a wear plate for the lever, a stop formed upon the wear plate to limit the movement of the lever, and springs engaging the lever substantially as and for the purposes set forth. 35

In testimony whereof I affix my signature in presence of two witnesses.

FRED S. FULLER.
